[57] CLAIM

The ornamental design for bicycle support, as shown and described.

DESCRIPTION

FIG. 1 is a perspective view of the bicycle support in an up position;

FIG. 2 is a perspective of the bicycle support of FIG. 10 in a down position;

FIG. 3 is an outer side view of the bicycle support in an up position;

FIG. 4 is an inner side view of the bicycle support in an up position;

FIG. 5 is a front view of the bicycle support in an up position;

FIG. 6 is a rear view of the bicycle support in an up position;

FIG. 7 is a top view of the bicycle support in an up position;

FIG. 8 is an underneath view of the bicycle support in an up position;

FIG. 9 is an outer side view of the bicycle support in a down position; and,

FIG. 10 is a rear view of the bicycle support in a down position.

The broken line showing of a partial bicycle in FIGS. 1 and 2 is for illustrative purposes only and forms no part of the claimed design.
